UNITED STATES PATENT OFFICE.

FRANK STREICH, OF CHICAGO, ILLINOIS.

WOODWORKING IMPLEMENT.

SPECIFICATION forming part of Letters Patent No. 715,173, dated December 2, 1902.

Application filed April 14, 1902. Serial No. 102,827. (No model.)

To all whom it may concern:

Be it known that I, FRANK STREICH, a citizen of the United States, residing at Chicago, in the county of Cook and State of Illinois, 5 have invented a new and useful Improvement in Woodworking Implements, of which the following is a specification.

My invention relates particularly to spoke-shaves; and my primary object is to provide 10 a simple device of the character indicated which can be readily adjusted, is capable of use in difficult situations, and can be used as either a right-handed or left-handed implement.

15 The preferred embodiment of my invention comprises a stock having a central body portion serving as a handle and lateral tapering extensions and attached cutting portions or bit-irons lying adjacent to said extensions.

20 My invention is shown in its preferred embodiment in the accompanying drawings, in which—

Figure 1 is a bottom plan view; Fig. 2, a side elevation of the rear or blunt edge of the 25 device; Fig. 3, a vertical section taken as indicated at line 3 of Fig. 2, and Fig. 4 a vertical section taken as indicated at line 4 of Fig. 2.

A represents the body portion, stock, or 30 handle, provided with flat under and upper surfaces a , a curved rear side surface a' , and a straight front side surface a'' . Extending in opposite directions from the handle and integral therewith are extensions B, having 35 slightly-concave upper surfaces b , surfaces b' lying in a plane projecting obliquely upward from the flat under surface a , surfaces b'' lying in a plane projecting slightly obliquely backward from the side flat surface 40 a'' , and surfaces b'' convergent to the surface b' . The edges of the described portions are rounded that the instrument may be freely handled without inconvenience.

The portion A is provided with longitudinal 45 slots or recesses a^3 .

C represents bit-irons or knives having shank portions c , provided with longitudinal slots c' and the pointed cutting portions c^3 in a plane oblique to the plane of the shank and 50 conforming approximately in outline to the outline of the cut-away portions of the extensions, the lower surfaces of the blades be-

ing approximately flush with the lower surfaces of the stock and its extensions. The cutting portions of the blades have thick rear 55 edges c^3 , which taper to keen cutting edges c^4 , lying in planes oblique to the under surface a and parallel with and adjacent to oblique edges c , formed by the front walls c^6 of the recesses b^4 , meeting the oblique surfaces b' . 60 The bit-irons or knives are adjustably secured by screws d , which pass through the slots c' and into the body portion A.

In use the implement is grasped at the stock or handle portion by either hand as desired. When used in one hand, the cutting edge of one knife is in proper position for use 65 and when grasped by the other hand the cutting edge of the knife is in proper position for use.

The implement is used as a shave in a well-understood manner, the oblique extension or knife-guard and the coacting oblique pointed cutting portion of the knife enabling the implement to be used in difficult situations. 70 Moreover, the unused oblique extension or knife-guard conforms to the shape of the hand, enabling a firm grip to be maintained 75 on the implement. By adjusting the knife longitudinally at its shank the cutting edge is moved parallel with the coacting edge of the guard, enabling a thicker or thinner shave to be cut at will.

Changes in minor details of construction within the spirit of my invention may be 80 made. Hence no undue limitation is to be understood from the foregoing detailed description.

What I claim as new, and desire to secure 85 by Letters Patent, is—

1. In an implement of the character described, the combination of a stock provided with an extension or knife-guard having a lower surface inclined upwardly and toward the extremity of the guard, and a suitably-90 attached knife with a cutting edge having a similar inclination and coacting with said guard.

2. In an implement of the character described, the combination of a stock provided 95 with a tapered extension or knife-guard having an oblique edge, and a knife suitably attached having a cutting edge adjacent to said edge of said knife-guard.

3. In an implement of the character described, the combination of a stock provided with a tapered extension or knife-guard having an oblique edge, and an adjustably-attached knife having a cutting edge adjacent to said edge of said knife-guard.
4. In an implement of the character described, the combination of a stock provided with a tapered extension or knife-guard having an oblique edge, and a knife adjustably attached by slot-and-pin connection at its shank with the stock, said knife having a cutting edge oblique to said shank and adjacent to said edge of said knife-guard.
5. In an implement of the character described, the combination of a stock provided with a tapered extension or knife-guard having an oblique surface, and a suitably-attached knife having a cutting edge adjacent to said surface of said knife-guard.
6. In an implement of the character de-

scribed, the combination of a stock having oppositely-extending knife-guards, and knives suitably attached having cutting edges adjacent to said guards.

25

7. In an implement of the character described, the combination of a stock having oppositely-extending knife-guards, and suitably-attached knives having cutting edges, disposed in the same direction, and adjacent to said knife-guards.

8. In an implement of the character described, the combination of a stock having oppositely-extending tapering extensions provided with knife-guards having oblique edges, and knives, tapering to points, suitably attached and having cutting edges adjacent to said edges of said knife-guards.
